Primary Examiner — Lilyana Bekic*Assistant Examiner* — Mary Shannon Malley(74) *Attorney, Agent, or Firm* — Shay Glenn LLP(57) **CLAIM**

The ornamental design for a jewellery box, as shown and described.

DESCRIPTION

FIG. 1 is a perspective front view of the jewellery box showing my new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof; and,

FIG. 9 is a front perspective view thereof, shown in an open configuration.

The broken lines in FIG. 9 illustrate portions of the jewellery box that form no part of the claimed design.
